RING

Sara H. Lashley, Atlantic City, N. J.

Application December 29, 1950, Serial No. 13,628

Term of patent 14 years

(Cl. D45—10)

To all whom it may concern:

Be it known that I, Sara H. Lashley, a citizen of the United States, residing at Atlantic City, in the county of Atlantic and State of New Jersey, have invented a new, original, and ornamental Design for a Ring, of which the following is a specification, reference being had to the accompanying drawing, forming part thereof.

In the drawing,

The figure is a perspective of the ring, showing my new design.

My design for a ring is characterized by the two contrasting, triangular stones with contiguous apices imbedded in and conforming with the peripheral contours of the ring circumference.

I claim:

The ornamental design for a ring, as shown and described.

SARA H. LASHLEY.
